UNITED STATES PATENT OFFICE.

JOHAN THEODOR BERNADOTTE SIDÉN, OF NYBO, WALBO, ASSIGNOR TO
AKTIEBOLAGET HASTSKYDDARE, OF STOCKHOLM, SWEDEN.

SPRING DRAFT OR TUG-LINK.

SPECIFICATION forming part of Letters Patent No. 357,419, dated February 8, 1887.

Application filed August 25, 1886. Serial No. 211,806. (No model.) Patented in Germany December 25, 1883, No. 29,259; in Sweden January 29, 1884, No. 18; in Belgium February 7, 1884, No. 64,085; in England February 8, 1884, No. 2,989; in France March 3, 1884, No. 160,926; in Norway May 20, 1884, and in Denmark July 22, 1884, No. 152.

To all whom it may concern:

Be it known that I, JOHAN THEODOR BERNADOTTE SIDÉN, a subject of the King of Sweden, and a resident of Nybo, Walbo, Sweden, have invented certain new and useful Improvements in Spring Tug-Links or Draft Attachments, (for which invention patents have been granted in Sweden, No. 18, dated January 29, 1884; in Belgium, No. 64,085, dated February 7, 1884; in Norway, dated November 20, 1884; in England, No. 2,989, dated February 8, 1884; in France, No. 160,926, dated March 3, 1884; in Denmark, No. 152, dated July 22, 1884, and in Germany, No. 29,259, dated December 25, 1883,) of which the following is a specification.

My invention relates to the class of spring tug-links or elastic draft attachments of which that shown in the patent of B. F. Rea, No. 175,164, of March 21, 1876, is a type. In this class of tug-links a coil-spring is inserted in the tug or trace, or at some point between the animal and the load, and two interlocked links, arranged within the hollow of the spring, are employed to limit the distention or extension of the same. In these tug-links the distention of the coil-spring and its contraction cause an axial twist, which produces a certain degree of distortion of the trace or tug and a chafing of the stop-links that serve to limit the degree of distention, and these devices are also lacking in stiffness transversely. In constructing my tug-link I avoid this difficulty by employing two coil or spiral springs oppositely wound, one spring arranged within the other, whereby the tendency to twist on the part of one spring counteracts or neutralizes that in the other. I also construct my stop-links in a peculiar manner, so that they mutually form guides for each other and are stiff to transverse strains.

In the drawings, which serve to illustrate my invention, Figure 1 is a side elevation of my elastic tug-link; and Fig. 2 is a sectional elevation showing the springs only in section, the stop-links being in elevation. Fig. 3 shows the links and tug-connections only, detached and in elevation; and Fig. 4 is a transverse section of said links on line *a* *a* in Fig. 3.

A and B represent two elongated coupled 50 links, having a substantially cylindrical cross-section, as seen in Fig. 4. Link A is furnished with a hook, A', and link B is furnished with an eye, B'. These might both be eyes or both be hooks. It is only essential that the links 55 be provided at their outer ends with some means whereby the device may be conveniently attached to the harness at one end (usually to the trace) and to the vehicle or load at the other end, (as to the double-tree of a wagon, 60 for example,) and these hooks or eyes may be formed integrally with the respective links or be attached thereto in any way. I prefer them integral, as shown.

On each link is formed a neck or reduced 65 part—C on the link A and C' on the link B. These are formed at the outer ends of the links and just beyond the outer ends of the slots in same.

Embracing the cylindrical overlapping portions of the links A and B are two spiral springs, D and E, oppositely wound, and these are contracted at their ends and made to embrace the necks C and C', formed on the links, as clearly shown in Fig. 2. The terminal coils 75 of the inner spring, D, closely embrace the links at their necks, while the terminal coils of the outer spring, E, (which incloses spring D,) embrace the links and the coils of the inner spring.

When one link, as B, is attached to a heavy load, and power is applied to the hook A' of link A, the springs D and E will be distended, the links sliding out on each other somewhat telescopically, and this extension of the springs 85 will continue until the tension of the springs is sufficient to overcome the load, or until the end bars of the links engage, which engagement serves as a stop to prevent further extension or the breaking of the springs by super-extension. The lengths of the slot-like openings in the links will of course govern the maximum extension of the springs.

As before intimated, when the spring of a draft-tug is distended longitudinally, it tends 95 to contract transversely and coil up tighter, and this of course tends to impart an axial twist to the two stop-links attached to its op-

posite ends. This twist is entirely obviated in my tug by employing two springs, one inclosed within the other, and said springs oppositely wound or coiled. This construction enables me to construct the stop-links, as shown, so as to serve mutually as guides for each other when the springs are distended. The bars of the links fit to each other somewhat in the manner of staves in a cask, the contiguous faces being beveled, as clearly seen in Fig. 4. In such a construction the links slide reciprocally on each other, and there is little or no play in any other than a longitudinal direction—that is to say, my two stop-links are not simply engaged like two loose links of a chain, they do not permit of any lateral or transverse flexure, and as the springs are connected rigidly to the necks of the stop-links, the said links prevent lateral flexure of the springs also.

My spring-tug is practically stiff with respect to transverse strains, and is exceedingly strong and durable.

Having thus described my invention, I claim—

1. The combination, in a spring draft-tug, of two interlocked links to form stops to limit the extension, two hooks or other attaching devices connected to said links, and two spiral springs, one embracing the other and wound in opposite directions, said springs inclosing

said links and secured at their ends to said hooks or other attaching devices.

2. The combination, in a spring draft-tug, of the two oppositely-wound springs D and E, the interlocked links, and the two attaching hooks or devices A' and B', said devices being connected firmly to said springs and formed integrally, respectively, with the said links.

3. The combination of the link A, provided with a neck, C, and a hook, A', the link B, interlocked with link A and provided with a neck, C', and an eye, B', and the oppositely-coiled springs D and E embracing said links, and attached at one end to the link A and at the other end to the link B, substantially as set forth.

4. The combination, with the two oppositely-coiled springs, of the two interlocked stop-links, connected together, as described, to form reciprocal guides for each other and to avoid lateral flexure, said springs attached firmly to said links and embracing or housing same, substantially as set forth.

In witness whereof I have hereunto signed my name in the presence of two subscribing witnesses.

JOHAN THEODOR BERNADOTTE SIDÉN.
